Primary Examiner—Robert M Spear
Assistant Examiner—Barbara B Lohr(57) **CLAIM**

The ornamental design for a shower curtain, as shown and described.

DESCRIPTION

FIG. 1 is a front elevated view of a shower curtain showing my new design;

FIG. 2 is a rear elevated view of the shower curtain; and,

FIG. 3 is a front perspective view of the shower curtain.

The broken lines depict the curtain rod and hangers used to support the shower curtain and form no part of the claimed design.
